UNITED STATES PATENT OFFICE.

ALSTON L. PRESTON, OF LEOMINSTER, MASSACHUSETTS.

BOW HOLDER.

Application filed June 1, 1923. Serial No. 642,833.

To all whom it may concern:

Be it known that I, ALSTON L. PRESTON, a citizen of the United States, residing at Leominster, in the county of Worcester and State of Massachusetts, have invented a new and useful Bow Holder, of which the following is a specification.

This invention relates to a bow holder capable of general use on various kinds of hair ornaments and devices on which a bow can be supported. The principal object thereof is to provide means for controlling the form of the bow and permitting of the folding of a ribbon used in connection therewith into a form which has not been possible, or at least convenient heretofore, and which can be completed and left in an attractive form with a comparatively small amount of ribbon, thus saving in the cost of the bow itself.

Reference is to be had to the accompanying drawings, in which—

Fig. 1 is an elevation of a barrette showing a preferred form of this invention, with a bow of ribbon attached thereto;

Fig. 2 is a similar view of the device without the bow;

Fig. 3 is a rear elevation;

Fig. 4 is an edge elevation;

Fig. 5 is a sectional view on the line 5—5 of Fig. 2 on an enlarged scale showing two positions of the bow holder;

Figs. 6 and 7 are respectively an elevation and edge view of a hairpin showing how the bow holder can be applied thereto;

Fig. 8 is a similar view showing it applied to a comb; and

Fig. 9 is a similar view showing the invention applied to another form of barrette.

Referring to the first five figures, it will be seen that the invention is shown as applied to a barrette 10 which can be considered as a support for the bow holder. It is shown in a form having its tongue 11 integral with it and connected to the back through a loop 12 and provided with a narrow shank 13 for entering between two integral projections 14 on the opposite end of the barrette and pointing rearwardly.

The barrette is provided with two perforations at 20 and 21 parallel with each other located preferably near the middle and one of them being of a width to receive a thickness of celluloid or other material of which the bow holder 22 is formed. The other one also has a portion of the same width

and length as the perforation 21 and is offset beyond it an equal distance but of narrower width.

The bow holder proper 22 consists preferably of a single sheet of celluloid, metal, or the like having a hinge portion 23 extending down from it on one side and a clasping tongue 24 of similar shape in general extending down on the other side and curved around toward each other at the bottom or rear. The hinge portion 23 is curved back on itself to form a passage for receiving a portion of the barrette 10 between the slot 21 and the edge of the barrette as indicated in Fig. 5 so that the whole device can swing as indicated by the dotted lines in that figure. The end of the tongue 24 is adapted to be received in the wide part of the slot 20 and it has a neck portion 75 above its extreme end adapted to be received in the narrow part of the slot afterwards to hold the bow holder down on the back of the barrette. In addition to this, the bow holder has two integral tongues 25 extending therefrom in opposite directions and bent downwardly preferably at an angle toward the body of the barrette. They are not intended to come into close contact with it, although they may, if desired. At any rate they are intended to come close enough to it to prevent the disengagement of a ribbon from it.

In using the device the bow holder is swung over to the dotted line position in Fig. 5 and the ribbon is located in position on a flat surface or in the hand as follows:

The end α can be considered as the starting end. The ribbon is taken back from that diagonally to form the part α' . Then it is folded over on itself to form an upper loop α^2 . This part of the ribbon is laid longitudinally across what may be considered the center of the device to form the front part α^3 of a corresponding loop or fold. The lower part of the same is drawn down under the rest of the bow and across it at the center to form another downwardly extending end α^4 . Of course the process may be reversed.

With the ribbon in this position it is applied to the body of the barrette without changing the relative positions of the parts. The prong or projection 25 on the right is located between the loop α^3 and the end α while the prong or projection 25 on the left is located between the loop α^2 and the

end α^4 . Of course the back or hinged part of the bow holder comes between the upper loops α^2 and α^3 while the fastening tongue 24 comes between the ends α and α^4 . With 5 the parts so arranged this fastening tongue is brought down into its slot and allowed to spring out into the narrow portion thereof. This fixes the bow in position and the article is then used as a single complete de- 10 vice in the ordinary way. It will be noted that as the ribbon is not tied a smaller amount of material is used than is ordinarily the case, and furthermore the ribbon is not wrinkled as much as it is in tying so 15 that it can be taken out and used over again conveniently.

On the second sheet of drawings I have shown several other ways in which the device can be used. The bow holder 22 is 20 shown substantially the same in all cases, but in Figs. 6 and 7 I have shown it as applied to a rearwardly extending portion 30 on a hair pin 31 which can be made of sheet celluloid and of course could be formed of 25 metal or celluloid wire. In this case the parts operate in the same way as on sheet one and there is no need of further description.

In Fig. 8 I have shown it as applied to a 30 comb 33 with no real modifications in the use of the bow holder itself except that, instead of being hinged at one side, it is made detachable as a whole by forming two 35 tongues 24 on it and omitting the hinge 23.

In Fig. 9 I have shown it as applied to 35 another device 34 adapted to be used on a braid of hair, and here also I have not modified the bow holder in any material manner.

Although I have illustrated and described 40 the invention as applied to only four different articles, I am aware of the fact that it can be made in many other forms and applied to articles of various kinds without departing from the scope of the invention 45 as expressed in the claims. Therefore I do not wish to be limited to all details of con-

struction herein shown and described, but what I do claim is:—

1. As an article of manufacture, a bow holder for application to a hair holding 50 support comprising a body of sheet material having two opposite projections for connecting it with the body of the support and having two other opposite projections at an angle to the first two spaced from the body 55 of the support at their ends.

2. As an article of manufacture, a bow holder for application to a hair ornament or hair holding device comprising a body having 60 two opposite projections for connecting it with the body of the device to which it is to be applied and having two other opposite projections at right angles to the first two for separating the folds of the 65 ribbon to facilitate the formation of a bow and the holding of it by this device.

3. As an article of manufacture, a bow holder for the purpose described comprising a central portion, a projection therefrom 70 constituting means for connecting it to an article to be worn in the hair, an opposite projection constituting a tongue diametrically opposite for connecting it with said article, and two opposite projections extending from between the first two, extending 75 at their ends toward the article on which it is worn for the purpose described.

4. As an article of manufacture, a bow holder for the purpose described comprising a central portion, a projection therefrom 80 having means for pivoting it to an article to be worn in the hair, an opposite projection constituting a tongue for connecting it with said article, and two opposite projections 85 in a plane at right angles to the first two arranged to be spaced at their ends slightly from the article on which it is worn for the purpose described.

In testimony whereof I have hereunto affixed my signature.

ALSTON L. PRESTON.
